[57] CLAIM

The ornamental design a for rotor for centrifugal machine,
as shown and described.

DESCRIPTION

FIG. 1 is a perspective view of the rotor for centrifugal machine showing my new design;

FIG. 2 is a front elevational view thereof;

FIG. 3 is a rear elevational view thereof;

FIG. 4 is a right side elevational view thereof, the left side
elevational view being identical thereto;

FIG. 5 is a top plan view thereof, the bottom plan view being
identical thereto;

FIG. 6 is a sectional view taken along line 6—6 of FIG. 2;
and,

FIG. 7 is a sectional view taken along line 7—7 of FIG. 2.
